(57) **CLAIM**

The ornamental design for a pipette tip, as shown and described.

DESCRIPTION

FIG. 1 is a perspective view of a pipette tip showing our new design;

FIG. 2 is an enlarged elevation view thereof;

FIG. 3 is a top plan view thereof; and,

FIG. 4 is a bottom plan view thereof.

The broken line showing of the lower portion of the tip is for illustrative purposes only and forms no part of the claimed design.
